(57) **CLAIM**

The ornamental design for a mobile battery charger, as shown and described.

DESCRIPTION

FIG. 1 is a top view of the mobile battery charger with port connector flaps closed;

FIG. 2 is a left-hand-side view of the mobile battery charger with port connector flaps closed;

FIG. 3 is a front view of the mobile battery charger with port connector flaps closed;

FIG. 4 is a right-hand-side view of the mobile battery charger with port connector flaps closed;

FIG. 5 is a rear view of the mobile battery charger with port connector flaps closed;

FIG. 6 is a bottom view of the mobile battery charger with port connector flaps closed;

FIG. 7 is a top view of the mobile battery charger with port connector flaps open;

FIG. 8 is a left-hand-side view of the mobile battery charger with port connector flaps open;

FIG. 9 is a front view of the mobile battery charger with port connector flaps open;

FIG. 10 is a right-hand-side view of the mobile battery charger with port connector flaps open;

FIG. 11 is a rear view of the mobile battery charger with port connector flaps open; and,

FIG. 12 is a bottom view of the mobile battery charger with port connector flaps open.

The broken lines shown in the drawings are included for the purpose of illustrating environmental structure and form no part of the claimed design.
